US00D753202S

(12) **United States Design Patent**
Traver

(10) **Patent No.:** US D753,202 S
(45) **Date of Patent:** ** Apr. 5, 2016

(54) **TRACK LOCKING HANDLE FOR A
WELDING TRACTOR**

(71) Applicant: **LINCOLN GLOBAL, INC.**, City of Industry, CA (US)

(72) Inventor: **Richard Dean Traver**, San Diego, CA (US)

(73) Assignee: **LINCOLN GLOBAL, INC.**, City of Industry, CA (US)

(**) Term: **14 Years**

(21) Appl. No.: **29/472,389**

(22) Filed: **Nov. 12, 2013**

(51) **LOC (10) Cl.** 15-09

(52) **U.S. Cl.**

USPC **D15/144**

(58) **Field of Classification Search**

USPC D8/316; D14/349; D15/144, 144.1, D15/144.2

(57) **CLAIM**

The ornamental design for a track locking handle for a welding tractor, as shown and described.

DESCRIPTION

FIG. 1 is a top perspective view of a track locking handle for a welding tractor showing my new design with environment shown in broken lines;

FIG. 2 is a bottom perspective view thereof;

FIG. 3 is a right side view thereof;

FIG. 4 is a left side view thereof;

FIG. 5 is a front side view thereof;

FIG. 6 is a rear view thereof;

FIG. 7 is a top view thereof; and,

FIG. 8 is a bottom view thereof.

The broken lines shown are environmental only and form no part of the claimed design.

1 Claim, 3 Drawing Sheets
